United States Patent Office.

HARRISON EATON, OF AMHERST, NEW HAMPSHIRE.

Design No. 2,535, dated January 1, 1867.

DESIGN FOR A STOVE.

The Schedule referred to in these Letters Patent and making part of the same.

TO ALL PERSONS TO WHOM THESE PRESENTS SHALL COME:

Be it known that I, HARRISON EATON, of Amherst, in the county of Hillsboro', and State of New Hampshire, have invented or produced a new and ornamental Design for a Soap-Stone Panelled Stove; and do hereby declare the said design to be represented in the accompanying drawings, of which—

Figure 1 denotes a front elevation; and

Figure 2, an end view of a stove containing such design.

The design in question is that of the body frame of the stove, and its fire-place door and door frame, the moulding and ornamentation thereof, constituting the said design, being exhibited in the drawings.

In such drawings, *a* is the top and *b* the bottom plate, and *c c c c* the corner posts of the frame; *d d d* are the legs, *e* the fire-place and register door frame, *f* the door thereof, and *g* the register. The panels are represented at *h h*, and the smoke-discharge pipe at *i*.

I claim the ornamental design as represented in the accompanying drawings.

HARRISON EATON.
